Patented Nov. 12, 1918.

FIG. 1.

INVENTOR.
JOHN P. RAYMOND
BY
Thomas S. J. Fox
ATTORNEY

UNITED STATES PATENT OFFICE.

JOHN P. RAYMOND, OF SAN FRANCISCO, CALIFORNIA.

ATOMIZING METHOD FOR MAKING FORMS AND CONTAINERS FROM FIBROUS COHESIVE SUBSTANCES.

1,284,926.

Specification of Letters Patent. Patented Nov. 12, 1918.

Application filed March 5, 1918. Serial No. 220,566.

To all whom it may concern:

Be it known that I, JOHN P. RAYMOND, a citizen of the United States, and a resident of the city and county of San Francisco and 5 State of California, have invented an Improvement in an Atomizing Method for Making Forms and Containers from Fibrous Cohesive Substances; and I do hereby declare the following to be a full, clear, and 10 exact description of my invention, such as will enable others skilled in the art to which it appertains to make and use the same.

This invention relates to an atomizing method of making forms and containers 15 from any suitable fibrous cohesive substances, such as wood or paper pulp and the like.

The objects of my invention are to facilitate the manufacture of the said forms and 20 containers; to improve the same; and to reduce the cost thereof.

My method consists of a series of operations which culminate in the production of the forms and containers.

25 In order that my invention may be clearly understood and readily practised the same is described with reference to the accompanying drawings, in which similar numerals indicate like parts.

30 The figure which is a side elevation, partly broken away and partly in section, illustrates one means which may be employed for carrying into effect the within described method. The same also shows the molds in 35 open position, and containers, each in dotted lines.

A mixture of fibrous cohesive pulp and water drawn from a suitable reservoir, not shown in the drawings, is let into a pneumatic tank, 2, through a pipe, 3, partially 40 filling the same, where it is constantly agitated by means of compressed air admitted through an inlet-pipe, 4, that portion of which within the tank is provided with 45 perforations, 5, connecting with a conveniently located air compressor. The space in the tank above the level of the mixture is filled with compressed air which exerts a force downward on the liquid mixture. The mixture 50 is then atomized and converted into a spray by means of a column of air expelled from the tank under compression through a nozzle, 8, and directed against a column of mixture expelled through a nozzle, 9, as 55 the mixture leaves the tank also under compression. The said mixture thus converted

into a spray is conducted into separable porous molds, 6. As the compressed air seeks to escape through the innumerable pores in the molds it drives before it the particles of 60 pulp in the atomized mixture, but as the pores in the molds are too small to permit the passage therethrough of the pulp particles the said pores are gradually plugged and a layer of pulp of uniform thickness is 65 gradually formed against the inner surfaces of the molds. The compressed air in seeking to escape will follow the line of least resistance and as soon as one pore is closed will pass out through those pores still open, 70 with the resultant action of plugging all pores alike. Synchronously the action of the compressed air packs the pulp particles firmly against the molds and forces the water in the atomized mixture out through the 75 pores in the molds. When the desired thickness of the layer of pulp thus produced has been attained the supply of mixture is stopped, and the column of compressed air is shut off. Connection is then established 80 between the molds and a vacuum tank, 7, for the purpose of dislodging any pulp particles comprising the containers thus produced that might possibly have become so embedded in the molds as to interfere with efficient removal.

Having thus described my invention, what I desire to claim and secure by Letters Patent, is:

1. The method of making fibrous forms 90 and containers consisting of the steps, first, agitating a mixture of fibrous pulp and water, second, atomizing a column of said mixture, and, third, in conducting into a porous mold by the action of air pressure 95 said atomized mixture for the purpose of forming a contiguous layer of pulp of any desired shape and thickness free from moisture.

2. The method of making fibrous forms 100 and containers consisting of the steps, first, agitating a mixture of fibrous pulp and water, second, atomizing a column of said mixture, third, conducting into a porous mold by the action of air pressure said 105 atomized mixture for the purpose of forming therein a contiguous layer of pulp of any desired shape and thickness free from moisture, and, fourth, in breaking any contact between said layer and said mold by the 110 action of vacuum.

3. The method of making forms and con-

tainers from fibrous substances consisting of conducting under air pressure into a porous mold a previously agitated and atomized mixture of pulp and water for the 5 purpose of forming a hollow container of any desired shape and thickness.

4. The method of making forms and containers from fibrous substances consisting of conducting under pressure into a porous 10 mold a previously agitated and atomized mixture of pulp and water for the purpose of forming a hollow container of any desired shape and thickness, and then dislodging said container from said mold by the 15 action of vacuum.

5. The method of making fibrous forms and containers consisting of first agitating a mixture of fibrous pulp and water, then atomizing said mixture by directing a 20 column of air under compression against a column of said mixture also under compression, and then forcing said atomized mixture under pressure into a porous mold for the purpose of shaping the container and 25 freeing the water in the atomized mixture.

6. The method of making fibrous forms and containers consisting of first agitating a mixture of fibrous pulp and water, then atomizing said mixture by directing a 30 column of air under compression against a column of said mixture also under compression, then forcing said atomized mixture under pressure into porous mold for the purpose of shaping therein the container and 35 freeing the water in the atomized mixture, and then breaking any contact between said container and said mold by the action of vacuum.

7. The method of making fibrous forms 40 and containers consisting in directing an air blast against a column of previously

agitated mixture of fibrous pulp and water for the purpose of atomizing said mixture, and then conducting said atomized mixture under air pressure into a porous mold for 45 the purpose of shaping a continuous layer of pulp of any desired form and thickness free from moisture.

8. The method of making fibrous forms and containers consisting in directing an air 50 blast against a column of previously agitated mixture of fibrous pulp and water for the purpose of atomizing said mixture, and then conducting said atomized mixture under air pressure into a porous mold for the purpose 55 of shaping therein a continuous layer of pulp of any desired form and thickness free from moisture, and then dislodging said layer of pulp from said mold by the action of vacuum.

9. The method of making fibrous forms and containers consisting of conducting into a porous mold by the action of air pressure an atomized mixture of fibrous pulp and water for the purpose of forming 65 therein a continuous layer of pulp of any desired shape and thickness free from moisture.

10. The method of making fibrous forms and containers consisting of conducting into 70 a porous mold by the action of air pressure an atomized mixture of fibrous pulp and water for the purpose of forming therein a continuous layer of pulp of any desired shape and thickness free from moisture, and 75 then breaking any contact between said layer and said mold by the action of applied vacuum.

In testimony whereof I have hereunto affixed my signature.

JOHN P. RAYMOND.
